UNITED STATES PATENT OFFICE.

ANTON J. ROLLERT, OF CHICAGO, ILLINOIS, ASSIGNOR TO THEODOR A. KOCHS, OF SAME PLACE.

DESIGN FOR A BARBER'S CHAIR.

SPECIFICATION forming part of Design No. 20,926, dated July 7, 1891.

Application filed June 15, 1891. Serial No. 396,379. Term of patent 3½ years.

To all whom it may concern:

Be it known that I, ANTON J. ROLLERT, a citizen of the United States, residing at Chicago, in the county of Cook and State of Illinois, have invented a novel Design for a Barber's Chair; and I do hereby declare the following to be a full, clear, and exact description of the invention, such as will enable others skilled in the art to which it appertains to make and use the same.

The design consists in the novel configuration and ornamentation for a barber's chair, as hereinafter described, and illustrated in the drawing.

15 The drawing is a perspective view of a barber's chair embodying my design.

Referring to said drawing, A indicates the base of the chair, and B the body portion thereof. The said body portion is provided 20 in a familiar manner with the seat, back, headrest, and arms. The arms terminate short of the front edge of the seat and have downwardly-extending and curved portions 1, which connect with the short posts 2 at the front corners of the seat. The posts 2 extend but 25 slightly above the ends of the curved portions 1 and are square at their bases and fluted and

pointed above said base portion. Beneath the arm and back of the curved portion 1 is a plain flat portion carved or ornamented to represent leaves or flowers. At the front ends 30 of the arms and above the curved portions are representations of lions or dragons' heads with the mouths open and tongues extended and curved downwardly and then upwardly, meeting the curved portions 1 near their front ends 35 adjacent the posts 2.

The parts of my design, when formed and assembled as shown and described herein, serve to add to the appearance of a barber's 40 chair and ornament the same in a highly-effective, symmetrical, and harmonious manner, which is agreeable and pleasing to the eye.

I claim as my invention— 45

The design for a barber's chair, substantially as shown and described.

In testimony whereof I affix my signature in presence of two witnesses.

ANTON J. ROLLERT.
